(57) **CLAIM**

We claim the ornamental design for a printer, as shown and described.

DESCRIPTION

FIG. 1 is a top perspective view of a printer showing our new design;

FIG. 2 is a front elevational view thereof;

FIG. 3 is a top plan view thereof;

FIG. 4 is a bottom plan view thereof;

FIG. 5 is a right end elevational view thereof;

FIG. 6 is a left end elevational view thereof;

FIG. 7 is a rear elevational view thereof;

FIG. 8 is a top perspective view of the printer of FIG. 1 illustrating a front panel of the printer in a closed position; and,

FIG. 9 is a top perspective view of the printer of FIG. 1 illustrating a digital camera (shown in phantom) docked to the printer.

The broken lines in the drawings are for illustrative purposes only and form no part of the claimed design.
